US0D1038379S

(12) **United States Design Patent** (10) Patent No.: **US D1,038,379 S**
(45) Date of Patent: ** Aug. 6, 2024

(54) **ON-BODY INJECTOR**

- (71) Applicant: **AMGEN INC.**, Thousand Oaks, CA (US)
- (72) Inventors: **Brian Stonecipher**, Newbury Park, CA (US); **Peter V. Shultz**, Woodland Hills, CA (US); **Lisa Nugent**, Malibu, CA (US); **Margaux Frances Boyaval**, Newbury Park, CA (US); **Sigrid Moeslinger**, New York, NY (US); **Masamichi Udagawa**, New York, NY (US)
- (73) Assignee: **AMGEN INC.**, Thousand Oaks, CA (US)
- (**) Term: **15 Years**
- (21) Appl. No.: **29/723,031**
- (22) Filed: **Feb. 4, 2020**

Related U.S. Application Data

- (62) Division of application No. 29/636,584, filed on Feb. 9, 2018, now Pat. No. Des. 878,559, which is a division of application No. 29/573,430, filed on Aug. 5, 2016, now Pat. No. Des. 813,380.
